ABSTRACT

A shipping vessel is disclosed. The shipping vessel includes a vessel segment and a control system to control the vessel segment. The shipping vessel includes at least one first variable ballast tank and at least one second variable ballast tank adjacently positioned to the at least one first variable ballast tank. The at least one control system configured to receive a subroute comprising a target peak, a target trough, a target course, and a target waypoint. Based on the subroute, the at least one control system configured to selectively operate the at least one first variable ballast tank and the at least one second variable ballast tank to alter a travel state of the vessel segment among a positive buoyancy, a negative buoyancy, and a neutral buoyancy.

**VARIABLE BALLAST PROPULSION
SHIPPING VESSEL, SYSTEMS AND
METHODS**

**CROSS REFERENCE TO RELATED
APPLICATIONS**

This present application is a Continuation Application-in-part of and claims the benefit of U.S. patent application Ser. No. 18/834,219, entitled “VARIABLE BALLAST PROPULSION SHIPPING VESSEL, SYSTEMS AND METHODS”, filed Jul. 29, 2024, which application claims the benefit of International Application No. PCT/US2023/037256, entitled “VARIABLE BALLAST PROPULSION SHIPPING VESSEL, SYSTEMS AND METHODS”, filed Nov. 14, 2023, which applications are incorporated herein by reference in their entirety.

FIELD OF THE INVENTION

The present invention relates generally to ocean freight shipping technology. More particularly, this invention pertains to assemblies, systems, and methods for maritime autonomous cargo shipping in both surfaced and submerged modes.

BACKGROUND OF THE INVENTION

Approximately 80 percent of goods constituting global trade are transported by ocean shipping, most carried inside 40-foot-long steel containers stacked by the thousands atop some of the largest vessels in the world. Between 1990 and 2021, the volume of cargo transported by ships grew from 4 billion tons to nearly 11 billion tons. Nearly 69 percent of all the goods traded by the United States of America are transported via waterways, predominantly by seagoing vessels. Ships transport over 41 percent of the total value of goods traded by the United States.

The supply chain delays caused by the coronavirus pandemic underscored both how crucial the maritime container trade is to the global economy, and how vulnerable ocean shipping is to catastrophic disruption. Pandemic-driven challenges caused the cost of shipping a container on the world's transoceanic trade routes to increase seven-fold in the 18 months following March 2020, while the cost of shipping bulk commodities spiked even more. Ship chartering costs surged by up to 773% since late May 2020. Marine fuel costs near tripled from \$155.5 per metric ton in April 2020 to \$435.5 per metric ton currently. The one-day cost of operating a 4,250-box ship spiked during that time from about \$30,200 per day in mid-June 2020 to about \$151,400 a day currently.

Ocean shipping at such a large scale has significant environmental impact, are responsible for more than 18 percent of certain air pollutants, including greenhouse gas emissions. The International Maritime Organization (IMO) estimates that carbon dioxide emissions from shipping were equal to 2.2% of the global human-made emissions in 2012 and expects such including air pollution, water pollution, acoustic noise, and oil pollution. Ships 30 emissions to rise 50 to 250 percent by 2050 if no action is taken.

What is needed are alternative systems and methods for timely, reliable, and affordable delivery of bulk freight and/or goods containers via ocean shipping. Specifically, ocean-going vessel designs that produce little or no hydrocarbons and, ideally, that do not use fossil fuels for propulsion are desired. Besides being more environmentally

2

friendly, employment of engines that do not burn fossil fuels holds promise for propulsion means that are less expensive to build, maintain, and/or repair than legacy engine technologies. Vessel designs with the advantage of autonomous control may be deployed without a manned crew, further lowering operating costs and eliminating human error. Vessel designs that support submerged mode operation may provide a safer method of transporting cargo across oceans due to natural protection from surface storms and high seas.

This background information is provided to reveal information believed by the applicant to be of possible relevance to the present invention. No admission is necessarily intended, nor should be construed, that any of the preceding information constitutes prior art against the present invention.

BRIEF DESCRIPTION OF THE DRAWINGS

The preferred embodiments of the invention will herein-after be described in conjunction with the appended drawings provided to illustrate and not to limit the invention, where like designations denote like elements, and in which:

FIG. 1 is a side elevation view schematic diagram of a variable ballast propulsion shipping vessel according to an embodiment of the present invention;

FIG. 2 is a side elevation view schematic diagram of an exemplary lead segment of the variable ballast propulsion shipping vessel of FIG. 1;

FIG. 3 is a front elevation cross-section view schematic diagram of the exemplary lead segment of FIG. 2 as viewed through line A-A;

FIG. 4 is a top elevation view schematic diagram of the exemplary lead segment of FIG. 2 with wings deployed;

FIG. 5 is a top elevation view schematic diagram of the exemplary lead segment of FIG. 2 with starboard wings retracted;

FIG. 6 is a side elevation view schematic diagram of an exemplary cargo segment of the variable ballast propulsion shipping vessel of FIG. 1;

FIG. 7 is a front elevation cross-section view schematic diagram of the exemplary cargo segment of FIG. 6 as viewed through line B-B;

FIG. 8 is a top elevation view schematic diagram of the exemplary cargo segment of FIG. 6;

FIG. 9 is a top elevation view schematic diagram of a tail segment of the variable ballast propulsion shipping vessel of FIG. 1;

FIG. 10 is a block diagram of a variable ballast propulsion shipping vessel control system according to an embodiment of the present invention;

FIG. 11 is a flowchart of exemplary computer-implemented logic for a Navigation Subsystem of the variable ballast propulsion shipping vessel control system of FIG. 8;

FIG. 12 is a flowchart of exemplary computer-implemented logic for a Train Glide Subsystem of the variable ballast propulsion shipping vessel control system of FIG. 8;

FIG. 13 is a flowchart of exemplary computer-implemented logic for a Segment Drive Subsystem of the variable ballast propulsion shipping vessel control system of FIG. 8;

FIG. 14 is a side elevation view schematic diagram of an exemplary slipstream adornment of the lead segment of FIG. 2;

FIG. 15 is a side elevation view schematic diagram of an exemplary slipstream adornment of the cargo segment of FIG. 5 with starboard wing folded;

FIG. 16 is a side elevation view schematic diagram of an exemplary slipstream adornment of the variable ballast propulsion shipping vessel of FIG. 1;

FIG. 17 is an exemplary illustration of a side elevation view of a vessel segment, in accordance with some embodiments of the present invention;

FIG. 18 is an exemplary schematic block diagram of interconnected ballast tanks provided in the exemplary vessel segment of FIG. 17, in accordance with some embodiments of the present invention;

FIG. 19 is an exemplary illustration of a front elevation cross-sectional view of the exemplary vessel segment of FIG. 17 as viewed through line A-A of FIG. 17, in accordance with some embodiments of the present invention; and

FIG. 20 is an exemplary illustration of a middle elevation cross-sectional view of the exemplary vessel segment of FIG. 17 as viewed through line B-B of FIG. 17, in accordance with some embodiments of the present invention.

FIG. 21 is a flow chart depicting an exemplary method for operating the shipping vessel of FIG. 17, according to some embodiments of the present invention.

As used herein, like reference numerals refer to like parts throughout the several views of the drawings.

DETAILED DESCRIPTION OF THE INVENTION

The present invention will now be described more fully hereinafter with reference to the accompanying drawings, in which preferred embodiments of the invention are shown. This invention may, however, be embodied in many different forms and should not be construed as limited to the embodiments set forth herein. Rather, these embodiments are provided so that this disclosure will be thorough and complete, and will fully convey the scope of the invention to those skilled in the art.

Although the following detailed description contains many specifics for the purposes of illustration, anyone of ordinary skill in the art will appreciate that many variations and alterations to the following details are within the scope of the invention. Accordingly, the following embodiments of the invention are set forth without any loss of generality to, and without imposing limitations upon, the claimed invention.

As used herein, the word "exemplary" or "illustrative" means "serving as an example, instance, or illustration." Any implementation described herein as "exemplary" or "illustrative" is not necessarily to be construed as preferred or advantageous over other implementations. All of the implementations described below are exemplary implementations provided to enable persons skilled in the art to make or use the embodiments of the disclosure and are not intended to limit the scope of the disclosure, which is defined by the claims.

Furthermore, in this detailed description, a person skilled in the art should note that quantitative qualifying terms such as "generally," "substantially," "mostly," and other terms are used, in general, to mean that the referred to object, characteristic, or quality constitutes a majority of the subject of the reference. The meaning of any of these terms is dependent upon the context within which it is used, and the meaning may be expressly modified.

In one aspect, a variable ballast propulsion shipping vessel is described. The shipping vessel includes a vessel segment and a control system to control the vessel segment. The shipping vessel includes one or more variable ballast tanks and at least one control system to selectively operate

the variable ballast tank(s) to alter a travel state of the vessel segment. As an example, the shipping vessel includes at least one first variable ballast tank and at least one second variable ballast tank adjacently positioned to the at least one first variable ballast tank. The shipping vessel also includes the at least one control system to selectively operate the at least one first variable ballast tank and the at least one second variable ballast tank to alter a travel state of the vessel segment. The at least one control system is configured to receive a subroute comprising a target peak, a target trough, a target course, and a target waypoint. Based on the subroute, the control system is configured to selectively operate the at least one first variable ballast tank and the at least one second variable ballast tank to alter a travel state of the vessel segment among a positive buoyancy, a negative buoyancy, and a neutral buoyancy, based on the subroute.

In another aspect, a method for operating a shipping vessel is disclosed. The shipping vessel includes a vessel segment, and at least one control system configured to control the vessel segment. The vessel segment includes at least one first variable ballast tank and at least one second variable ballast tank adjacently positioned to the at least one first variable ballast tank. The method includes receiving, by the at least one control system, a subroute comprising a target peak, a target trough, a target course, and a target waypoint. Based on the subroute, the method includes selectively operating, by the at least one control system, the at least one first variable ballast tank and the at least one second variable ballast tank to alter a travel state of the vessel segment among a positive buoyancy, a negative buoyancy, and a neutral buoyancy, based on the subroute.

In general, the present invention relates to a variable ballast propulsion submersible vessel for transporting removable cargo (e.g., fluid or dry bulk freight, goods in shipping containers). The submersible in one embodiment comprises one water-tight, cargo-carrying vessel segment. Alternatively, the submersible may comprise substantially identical water-tight, cargo-carrying segments connected sequentially by respective mating hinge mechanisms. Each segment may be selectively attached and detached from the next adjacent segment, allowing variable length "trains" to be assembled and moved by water in both submerged and surfaced modes.

The vessel segment or each cargo-carrying segment may be largely a slave to external control by a detachable bow-and/or stern-based computerized control system (e.g., an onboard computer, local area network, and long-haul communication link to a remote navigation system; alternatively, an onboard computer and stored navigation data and undersea topographical maps, to govern navigation along a pre-recorded sail plan; also alternatively, an on-board computer monitoring onboard environmental sensors and executing real-time autonomous navigation rules (e.g., artificial intelligence) to determine and execute a non-recorded sail plan).

In certain embodiments, a single vessel segment or alternatively an assembled vessel may be designed to operate at depths from 3 to 20,000 feet while underway for long-haul navigation. At both the beginning and end of a delivery "sortie", the single vessel segment or alternatively assembled vessel may operate in surfaced mode in and around a port area, optionally assisted by one or more local port-based service vessels capable of towing assembled (e.g., "trains") and/or an individual vessel segment or sections of the vessel segments loaded with cargo. As the vessel segments are quickly unloaded and reloaded, they may be redeployed or alternatively reattached as part of the train supporting another delivery sortie. The port-based service

vessel(s) may tow the single vessel segment or assembled segments from an origination port area back out to sea where the reloaded vessel may then be sent on its way to the next required delivery destination. One cargo-carrying vessel segment may be a theoretical minimum number of segments required for certain embodiments of the present invention to operate (e.g., to create variable buoyancy motion).

Variable ballast propulsion may be defined as the bow- and/or stern-based computer-based control system coordinating oscillation of the respective ballasts present in the single vessel segment or alternatively each cargo segment of an assembled train of cargo segments. The timing of electrically triggered ballast intake and exhaust ports onboard the vessel segment may create an underwater gliding up and down motion among the single vessel segment or the train of cargo segments. The control system may similarly operate directional components present on the external structure of the single vessel segment or each cargo segment in the train. Such components may translate the simple up and down motion created by a given cargo segment into pitch (e.g., planes actuating from paired, side-mounted wings) and/or yaw (e.g., a rudder actuating from a dorsal wing).

More specifically, computer-based control system may cause water to enter a ballast tank of the vessel segment, creating negative buoyancy. Now in a negative buoyancy state, the segment may descend on a glide path to a predetermined depth before the computer-based control system may suddenly cause air to be pumped into the ballast tank of the segment to change the buoyancy state to positive. Behaving much like a glider, the computer-based control system may electrically trigger the aerodynamic features (e.g., planes, rudders) of the vessel segment or of each cargo segment to exploit both its negative and positive buoyancy states by translating the either downward or upward acceleration into a desired direction (as a combination of pitch and/or yaw). Emergency system failures may be dealt with by a depth sensor that may trigger airbags to be deployed past a certain depth and/or when desired forward motion is somehow lost.

In certain embodiments, the minimal power source onboard a given vessel segment or a cargo segment to operate the variably buoyancy propulsion "engine" is an electric battery that may be recharged while the segment is underway, for example, using impellers mounted on the respective sides/top of each segment and electrically connected to small battery chargers (e.g., alternators). Designs that use battery power to manipulate ballast equipment onboard individual segments may advantageously result in a vessel that uses less hydrocarbons than legacy container ships. Battery-stored electrical power on each segment alternatively may be replenished by optional onboard charging systems such as solar panels (e.g., when a vessel is surfaced), water or wind turbine chargers (e.g., when moving underwater or when surfaced in moving air), and/or inverter/charger (e.g., when connected to shore power).

Without the need for fossil fuels for propulsion, the present shipping design may be much more environmentally friendly than traditional shipping options. Without the need for engines burning fossil fuels, the need for expensive and reoccurring maintenance and/or repairs of engines and equipment may advantageously be reduced. The vessel described herein may be autonomous and requires no crew, further lowering costs, and may be a vastly safer method of transporting cargo across oceans and seas due to the submersible capabilities of the vessel (i.e., no need to contend with storms and surface waves, with reefs and obstructions, and/or with shallow water).

Referring initially to FIG. 1, a variable ballast propulsion shipping vessel 100 according to an embodiment of the present invention will now be described in detail. In the exemplary configuration of FIG. 1, the shipping vessel 100 may comprise a lead segment 102 mechanically attached to a first of some number of cargo segments 104 which are mechanically attached to each other, in series, before ending with a mechanically attached tail segment 106.

Still referring to FIG. 1, and referring additionally to FIG. 2, the lead segment 102 may be characterized by a superstructure comprising a nose cone 202 (i.e., defining a bow) mounted forward of a lead body portion 203. A fixed ballast 206 may be mounted to a bottom of the lead body portion 203, for example, and without limitation, to maintain stability of the lead segment 102 when operating both in submerged and surfaced modes. An aft hinge mechanism 212 may be mounted to the lead body portion 203 opposite the nose cone 202, for example, and without limitation, to facilitate mechanical attachment to an assembled "train" of vessel segments 104, 106 to be operated by the lead segment 102.

Still referring to FIG. 2, and referring additionally to FIGS. 3, 4 and 5, the lead segment 102 may further comprise some number of port and starboard glide wings 220 configured to project pairedly and laterally (with respect to a centerline) from the lead body portion 203. The exemplary embodiment illustrated in FIGS. 2, 3, 4 and 5 comprises two pairs of glide wings 220 (four wings total). Those skilled in the art will readily appreciate that lead segment 102 designs, as well as cargo segment 104 designs described hereinbelow, may comprise a single pair of wings, or three (3) or more pairs of wings, while still accomplishing the many goals, features and advantages according to the present disclosure.

As illustrated in FIG. 3, each of the glide wings 220 may present a respective substantially flat bottom surface which may augment a substantially flat bottom of the fixed ballast 206 to present a hydrodynamic glide effect when the lead segment 102 is underway, and particularly in submerged mode. Each glide wing 220 may include at least one plane 222 that may be operated in combination with the wing planes 222 of the other glide wings 220 deployed, for example, and without limitation, to control lead segment 102 pitch and, with forward motion, to control lead segment 102 depth. Additionally, a dorsal wing 240 having a rudder 242 may be mounted to a top of the lead body portion 203, for example, and without limitation, to provide a primary control surface for selectively steering the lead segment 102 generally to port and/or to starboard.

Various accessories mounted on an exterior of lead segment 102 each may be configured as watertight assemblies to prevent water intrusion. For example, and without limitation, a navigation light 230 may be mounted at the bow of nose cone 202 for use as a safety beacon during night or reduced visibility navigation. Also, for example, and without limitation, environmental profiling gear 201 (e.g., instruments for measuring temperature, salinity, and/or pressure) may be mounted external to the nose cone 202 and/or to the lead body portion 203. Also, for example, and without limitation, a networking cable with plug 232 may be mounted at the stern of the lead body portion 203 for use in delivery of electric power and/or communication signals to "train" vessel segments 104, 106, as described in more detail hereinbelow. The lead segment 102 may further comprise an access panel 207 that may be opened when the lead segment 102 is in surfaced mode or when dry docked to allow maintenance access to components and systems that may be deployed either partially or fully inside the superstructure

202, 203 of the lead segment 102. For example, and without limitation, some number of impellers 208 may be configured to partially project from the exterior of lead segment 102 to translate movement of the lead segment 102 in submerged mode into spinning of the impeller(s) that, in turn, may be converted by a battery charger 310 into electrical current for power storage into an onboard battery bank 312.

The battery bank 312 may be used to power various substantially mechanical onboard systems including motors (not shown) used to actuate the planes 222 of the glide wings 220, and/or rudder(s) 242 of the dorsal wing(s) 240. Other substantially mechanical onboard systems powered by the battery bank 312 may include ballast intake(s)/exhaust(s) 302 used to selectively receive or expel water into/out of a variable ballast tank(s) 304; an air compressor 305 used to fill a compressed air tank 306 from which air may be introduced into the variable ballast tank(s) 304 to expel water for purposes of changing buoyancy of the lead segment 102; and a motor (not shown) used to actuate retractable and/or stowable components such as a global positioning system (GPS) antenna 210, the glide wings 220 (showing starboard wings retracted in FIG. 5), and/or the dorsal wing 240. The battery bank 312 also may be used to power shipping vessel control system 320 components and electronic devices (e.g., on-board computer; local area networking, long-haul communications, onboard sensors).

Referring now to FIGS. 6, 7 and 8, each cargo segment 104 may be characterized by a superstructure comprising a cargo body portion 403 that may include at least one sealable access mechanism. For example, and without limitation, a cargo door 404 may be configured for top loading/unloading of cargo organized into containers shaped to substantially fit an interior cargo bay 455 of the cargo body portion 403. Also, for example, and without limitation, a hatch 405 and/or a capped filler neck 407 may be configured for fill and/or retrieval of loose bulk cargo (e.g., grain, sand, gravel) and/or fluid cargo (e.g., oil, gas) to/from any number of advantageously arranged onboard cargo tanks 455. A person of skill in the art will immediately recognize that an advantageous implementation of needed sealable access mechanisms may be bottom-mounted (e.g., for gravity drain) rather than and/or in addition to top-mounted on the cargo body portion 403.

A fixed ballast 406 may be mounted to a bottom of the cargo body portion 403, for example, and without limitation, to maintain stability of the cargo segment 104 when operating both in submerged and surfaced modes. A forward hinge mechanism 410 and an aft hinge mechanism 412 may be mounted to a bow and a stern, respectively, of the cargo body portion 403, for example, and without limitation, to facilitate mechanical attachment in line as part of the assembled “train” of vessel segments 104, 106 as operated by the lead segment 102. Each cargo segment 104 may further comprise some number of port and starboard glide wings 420 configured to project pairedly and laterally (with respect to a centerline) from the cargo body portion 403. Each of the glide wings 420 may present a respective substantially flat bottom surface which may augment a substantially flat bottom of the fixed ballast 406 to present a hydrodynamic glide effect when the cargo segment 104 is underway in submerged mode. Each glide wing 420 may include at least one plane 422 that may be operated in combination with the wing plane(s) 422 of the other glide wing(s) 420 deployed, for example, and without limitation, to control cargo segment 104 pitch and, with forward motion, to control cargo segment 104 depth. Additionally, a dorsal wing 440 having a rudder 442 may be mounted to a

top of the cargo body portion 403, for example, and without limitation, to provide a primary control surface for selectively steering the cargo segment 104 generally to port and/or to starboard.

5 Various accessories mounted on an exterior of cargo segment 104 each may be configured as watertight assemblies to prevent water intrusion. For example, and without limitation, a networking cable receptacle 430 may be mounted forward on the cargo body portion 103; and a 10 networking cable with plug 432 may be mounted at the stern of the cargo body portion 403. A reconfigurable bus for delivery of electric power and/or communication signals from lead segment 102 to a “train” of cargo segments 104 may be formed by using each networking cable receptacle 15 430 to fittedly receive the respective networking cable with plug 432 of the adjacent vessel segment 102, 104 in the assembled “train”.

Each cargo segment 104 may further comprise components and systems that may be deployed either partially or 20 fully inside the cargo body portion 403 of cargo segment 104. For example, and without limitation, some number of impellers 408 may be configured to partially project from the exterior of cargo segment 104 to translate movement of the cargo segment 104 in submerged mode into spinning of the impeller(s) 408. Similar to the description above for the lead segment 102, the spinning of the impeller(s) 408, in turn, may be converted by a battery charger 510 into electrical current for power storage into an onboard battery bank 512. This battery bank may be used to power various 25 substantially mechanical systems onboard cargo segment 104 including motors (not shown) used to actuate the planes 422 of the glide wings 420, and/or rudder(s) 442 of the dorsal wing(s) 440. Other substantially mechanical systems onboard the cargo segment 104 and powered by the battery bank 512 may include motors (not shown) used to actuate ballast ports 502 used to selectively receive or expel water into/out of a variable ballast tank(s) 504; an air compressor 305 used to fill a compressed air tank 506 from which air may be introduced into the variable ballast tank(s) 504 to 30 35 40 segment 102 through the “train” of cargo segments 104 to the tail segment 106 may be terminated by using the networking cable receptacle 580 to fittedly receive the networking cable with plug 432 of the last cargo segment 104 in the assembled “train.”

The tail segment 106 may further comprise components and systems that may be deployed either partially or fully inside the tail body portion 542 of the tail segment 106. For example, and without limitation, an onboard battery bank (not shown) may be used to power various substantially mechanical systems onboard the tail segment 106 including motors (not shown) used to actuate a deployable drogue (not shown). Other substantially mechanical systems onboard the tail segment 106 and powered by the battery bank (not shown) may include ballast intake(s)/exhaust(s) (not shown) used to selectively receive or expel water into/out of a variable ballast tank(s) (not shown); an air compressor (not shown) used to fill compressed air tank (not shown) from which air may be introduced into the variable ballast tank(s) to expel water for purposes of changing buoyancy of the tail segment 106. The battery bank also may be used to power electronic devices (e.g., actuator/ballast controls, local area networking relays, sensors) found onboard the tail segment 106 that may be largely operated by the shipping vessel control system 320 of the lead segment 102.

Referring now to the schematic block diagram of FIG. 10, a variable ballast shipping vessel control system 320 is illustrated in accordance with an exemplary embodiment of the present invention. Those skilled in the art will understand that the principles of the present disclosure may be implemented on or in data communication with any type of suitably arranged device or system configured to automate submerged mode and water surface mode vessel navigation and control.

In the exemplary configuration shown in FIG. 10, the variable ballast shipping vessel control system 320 may comprise a processor 612 (also referred to herein as a “microprocessor” or “central processing unit (CPU)”) that may be operable to accept and execute computerized instructions, and also a data store 614 that may store data and instructions used by the processor 612. The processor 612 may be positioned in data communication with electrical/computing devices served by a bus that may be configured to direct input from such devices to the data store 614 for storage and subsequent retrieval. For example, and without limitation, the processor 612 may be configured in data communication with networked resources (e.g., a local area network (LAN) 630) via an underwater-capable short-range wireless interface 608 and/or via a wired data port interface 610. Using such data interfaces, processor 612 may be configured to direct input received from components of the LAN 630 to the data store 614 for storage. Similarly, the processor 612 may be configured to retrieve data from the data store 614 to be forwarded as output to various components of the LAN 630. More specifically, networked components may include each cargo segment’s onboard control devices 640 and/or the tail segment’s onboard control devices 650.

For example, and without limitation, the computerized instructions of the variable ballast shipping vessel control system 320 may be configured to implement a Navigation Subsystem 622, a Train Glide Subsystem 624, and/or a Segment Drive Subsystem 626 that may be stored in the data store 614 and retrieved by the processor 612 for execution. The Navigation Subsystem 622 may be operable to implement functionality as described below for FIG. 11 related to receipt and execution of a high-level sail plan to guide vessel

navigation. The Train Glide Subsystem 624 may be operable to implement functionality as described below for FIG. 11 related to intermediate-level commands to coordinate formation and operation of a set of cargo segments configured as a “train.” The Segment Drive Subsystem 626 may be operable to implement functionality as described below for FIG. 13 related to low-level commands to manipulate the local mobility components of each segment of the “train.”

Referring now to FIG. 11, a method aspect of Navigation Subsystem 622 will now be described in detail. From the start at Block 701, configuration variables (e.g., number of cargo segments 104 employed; container identifiers and cargo weights/type for each) may be received and processed to initialize the assembled “train” (Block 710). Navigation detail then may be received/retrieved defining a delivery sortie (e.g., origin, destination, preloaded navigation maps, course outline) at Block 720. At Block 730, input sortie details may be used to calculate a detailed delivery course in the form of queued subroutines that collectively span the uninterrupted distance from sortie origin to sortie destination. For example, and without limitation, each subroutine may comprise a start waypoint and an end waypoint, between which may be defined an elemental glide maneuver for the assembled “train” (e.g., from an initial peak depth down to trough depth, and back up to a subsequent peak depth).

After a complete set of subroutines is queued and the onboard GPS detects that the “train” is at the sortie origin waypoint (Block 735), the Navigation Subsystem 622 may execute the first subroutine in the queue to get underway. As shown at Block 740, the first subroutine may be a tow out subroutine which may involve moving the assembled “train” in surfaced mode (e.g., towed by one or more tugboats) out of a port of embarkation (e.g., from the sortie origin waypoint) and to a location from which the “train” may begin navigating autonomously (e.g., the next queued subroutine’s start waypoint). For the duration of the special case tow out subroutine, surfaced mode operation may entail the peak depth and trough depth settings for the entire maneuver to remain equal to the unsubmerged draft of the “train” of segments.

At Block 745, Navigation Subsystem 622 may continually monitor “train” location by GPS for the end waypoint of the tow out subroutine (also referred to herein as the “stage out” waypoint). Upon detection of stage out reached, the next subroutine in the queue may be pulled (Block 748) and executed (Block 750). This pull and execute cycle may continue until the start waypoint of a tow in subroutine (also referred to herein as the “stage in” waypoint) is detected at Block 775. Because autonomous operation of an assembled “train” as described above is based on translating synchronized variable buoyancies of the “train” segments into generally forward oscillating motion, most pulled (Block 748) and executed (Block 750) subroutines may define a respective glide maneuver comprising diving the “train” from a start waypoint at a peak depth toward a target trough depth to pick up speed; and then ascending the “train” from the achieved trough depth toward a next target peak depth to complete the elemental glide maneuver.

Special purpose subroutines may be interspersed in a delivery sortie queue to bring one or more of the “train” segments to the water surface (e.g., peak depth and/or trough depth equal to or near the unsubmerged draft) to accomplish certain surface mode operations (e.g., global positioning system (GPS) ping; satellite-based data communications; rendezvous at sea; approach to stage in). Also, in the event that sortie progress fails (e.g., the stage in waypoint is not detected within tolerance at Block 775, but the queue of

subroutines is emptied at Block 748), Navigation Subsystem 622 may be configured to dynamically calculate and queue one or more corrective subroutines (Block 760) and to execute these corrective subroutine(s) (Block 770) in an attempt to reach the planned stage in waypoint.

When the subroutine pull and execute cycle ultimately results in detection of the stage in waypoint (Block 775), the Navigation Subsystem 622 may execute the last subroutine in the queue (Block 780), which may be a tow in subroutine that may involve moving the assembled “train” in surfaced mode (e.g., towed by one or more tugboats) into a port of debarkation (e.g., at the sortie destination waypoint) where delivered cargo may be offloaded. For the duration of this special case tow in subroutine, surfaced mode operation may entail the peak depth and trough depth settings for the entire maneuver to be equal to the unsubmerged draft of the “train” of vessels. When, at Block 785, Navigation System 622 detects arrival at the sortie destination, shutdown protocols may be executed at Block 790 (e.g., compile operations log; capture and upload sortie debrief) before the process ends at Block 799.

Referring now to FIG. 12, a method aspect of Train Glide Subsystem 624 will now be described in detail. From the start at Block 801, configuration variables forwarded by calling Block 710 of FIG. 11 may be received and used to execute a verification test that the assembled “train” at Block 820 (e.g., configuration meets specifications; inter-segment systems operable and communicating). If an error in train assembly is detected at Block 825, control is returned to the calling Block 710 of FIG. 11 for corrective action. Confirmation of a successful verification test at Block 825 readies the Train Glide Subsystem 624 to receive and process an input subroutine.

More specifically, at Block 830, Train Glide Subsystem 624 may receive from calling Block 740 of FIG. 11 the first queued subroutine of a delivery sortie to be executed. For example, and without limitation, this first subroutine may be a tow out sequence. At Block 840, navigation components onboard the lead segment 102, cargo segment(s) 104, and/or tail segment 106 may be polled to determine real-time travel state variables (e.g., actual position, actual depth, actual heading) to be compared against the active subroutine (e.g., target position, target depth, target waypoint). If, at Block 852, an expected kickout condition (e.g., subroutine end waypoint and target depth reached) or an unexpected kickout condition is detected (e.g., subroutine trough depth exceeded), control may be returned to calling Block 740 of Navigation Subsystem 622 requesting further direction (e.g., next subroutine).

Until a kickout condition is detected at Block 852, Train Glide Subsystem 624 may loop through a series of synchronized commands to operate each of the cargo segments 104 to contribute to satisfaction of the input subroutine as a “train” assembly. For the tow out subroutine, for example, if at Block 855 the actual depth of each segment 102, 104, 106 equates to surface mode (e.g., unsubmerged draft), then all segments 102, 104, 106 may be commanded to execute neutral buoyancy (Block 860). Assuming tow out subroutine initial peak and trough are similarly set to surface mode, then detection of an actual depth above the target trough (that is, no longer in the water) may be considered impossible at Block 865. Continuing, if an actual depth below the target peak (e.g., unsubmerged draft) is detected at Block 875, then some or all segments 102, 104, 106 may be commanded to execute positive buoyancy (Block 880) to return the vessel to surface mode. During this simple tow out scenario, the assisting tugboats may be assumed to correctly direct the “train”

assembly on course to the end waypoint of the tow out subroutine. In response to detecting that the “train” assembly is on course (Block 889), all segments 102, 104, 106 may be commanded to execute maintain heading (Block 894), thereby cooperating with the steering actions of the assisting tugboats.

Arrival at the stage out waypoint may satisfy a kickout condition (Block 852) that prompts Navigation Subsystem 662 to begin looping through active autonomous subroutines 10 (Block 748 at FIG. 9). At Block 830, Train Glide Subsystem 624 may receive from calling Block 740 or Block 750 of FIG. 11 the next queued subroutine of the delivery sortie to be executed. As described above, each queued subroutine may define a respective glide maneuver comprising diving the 15 “train” from a start waypoint at a target peak depth toward a target trough depth; and then ascending the “train” from the achieved target trough depth toward a next target peak depth to complete the elemental glide maneuver. At Block 840, navigation components 555 (e.g., depth gauges, gyroscopes) onboard the lead segment 102, cargo segment(s) 104, and/or tail segment 106 may be polled to determine 20 real-time travel state variables (e.g., actual position, actual depth, actual course) to be compared against the active subroutine (e.g., target waypoint, target trough depth, target peak depths). If, at Block 852, an expected kickout condition 25 (e.g., subroutine end waypoint reached) or an unexpected kickout condition is detected (e.g., subroutine trough depth exceeded), control may be returned to calling Block 740 requesting further direction (e.g., next subroutine).

If at Block 855 the actual depth of each segment 102, 104, 30 106 matches the target depth, then all segments 102, 104, 106 may be commanded to execute neutral buoyancy (Block 860). If at Block 865 the actual depth of each segment 102, 104, 106 is above the target trough, then each of the “train” 35 segments 102, 104, 106 may be commanded, in rolling sequence forward to aft, to execute negative buoyancy (Block 870) to accomplish the planned descent. If at Block 875 the actual depth of each segment 102, 104, 106 is below the target peak, then each of the “train” segments 102, 104, 40 106 may be commanded, in rolling sequence forward to aft, to execute positive buoyancy (Block 880) to accomplish the planned ascent. During all buoyancy manipulations (and particularly for descent and ascents), the actual heading of the “train” vessel may be compared against the target course 45 for the active subroutine. If at Block 889 the target heading is determined to be on course within a set tolerance, if any, then all segments 102, 104, 106 may be commanded to execute maintain heading (Block 894). If at Block 887 the target heading is determined to be errant to port of the 50 planned course outside a set tolerance, if any, then each of the “train” segments 102, 104, 106 may be commanded, in rolling sequence forward to aft, to execute a turn to starboard (Block 880) to tend back on course. If at Block 885 the target heading is determined to be errant to starboard of the 55 planned course outside a set tolerance, if any, then each of the “train” segments 102, 104, 106 may be commanded, in rolling sequence forward to aft, to execute a turn to port (Block 890) to tend back on course. At Block 852, if either an expected kickout condition (e.g., subroutine end waypoint reached) or an unexpected kickout condition is detected (e.g., subroutine trough depth exceeded), control may be returned to calling Block 740 with a request for further 60 direction (e.g., next subroutine).

Exhausting autonomous operation subroutines routinely 65 may lead to detection of the stage in waypoint of the delivery sortie (Block 775 of FIG. 11) leading to execution of the tow in subroutine. More specifically, at Block 830, Train Glide

Subsystem 624 may receive from calling Block 780 of FIG. 11 the tow in subroute of the delivery sortie to be executed. At Block 840, navigation components onboard the lead segment 102, cargo segment(s) 104, and/or tail segment 106 may be polled to determine real-time travel state variables (e.g., actual position, actual depth, actual course) to be compared against the tow in subroute (e.g., target waypoint, target trough depth, target peak depths). If, at Block 852, an expected kickout condition (e.g., destination reached) or an unexpected kickout condition is detected (e.g., tow in trough depth exceeded), control may be returned to calling Block 780 requesting further direction (e.g., emergency safety deployment of ballasts).

If at Block 855 the actual depth of each segment 102, 104, 106 equates to surface mode (e.g., unsubmerged draft), then all segments 102, 104, 106 may be commanded to execute neutral buoyancy (Block 860). Assuming tow in subroute initial peak and trough are similarly set to surface mode, then detection of an actual depth above the target trough may be considered impossible at Block 865. Continuing, if an actual depth below the target peak (e.g., unsubmerged draft) is detected at Block 875, then some or all segments 102, 104, 106 may be commanded to execute positive buoyancy (Block 880) to return the vessel to surface mode. During the simple tow in scenario, the assisting tugboats may be assumed to correctly direct the “train” assembly on course to the end waypoint (e.g., sortie destination) of the tow in subroute. In response to detecting that the “train” assembly is on course (Block 889), all segments 102, 104, 106 may be commanded to execute maintain heading (Block 894), thereby cooperating with the steering actions of the assisting tugboats. Arrival at the destination may satisfy a kickout condition (Block 852) that may capture and upload sortie metrics to Navigation Subsystem (Block 785 of FIG. 11) in support of execution of system shutdown protocols (Block 790 at FIG. 11) before the method ends at Block 799.

Referring now to FIG. 13, a method aspect of Segment Drive Subsystem 626 will now be described in detail. A person of skill in the art will appreciate that the independent, yet synchronized, operation of a plurality of cargo segments lends itself to simultaneous execution of multiple instances of Segment Drive Subsystem 626, including employment of multiprocessing. From the start at Block 901, a local systems power up test may be performed for each cargo segment comprising the assembled “train” (Block 901). If any of the segment’s tests throws an error, control may be returned to the calling Block 820 of FIG. 12 and, ultimately, to the calling Block 710 of FIG. 11 for corrective action. A successful set of segments tests at their respective Blocks 915 may ready each Segment Drive Subsystem 626 to receive and process an elemental glide maneuver command in support of the active subroute.

More specifically, at Block 920, Segment Drive Subsystem 626 may receive from one of the calling Blocks 890, 892, 894 of FIG. 12 a maneuver command comprising, for example, and without limitation, a buoyancy target and a turn target. If, at Block 925, the buoyancy target of the maneuver command is determined to request an ascend (e.g., positive buoyancy), then at Block 930 onboard local control devices may operate the ballast to fill with air and expel water; may operate the port plane to actuate up; may operate the starboard plane to actuate up; and may operate the dorsal rudder to remain at nominal. If instead, at Block 935, the buoyancy target of the maneuver command is determined to request a descent (e.g., negative buoyancy), then at Block 940 onboard local control devices may operate the variable ballast to fill with water and recapture (e.g.,

compress and store onboard) the expelled air; may operate the port plane to actuate down; may operate the starboard plane to actuate down; and may operate the dorsal rudder to remain at nominal. If instead, at Block 945, the buoyancy target of the maneuver command is determined to request a depth hold (e.g., neutral buoyancy), then at Block 950 onboard local control devices may operate the variable ballast to remain nominal (e.g., hold steady the existing air and/or water in ballast); may operate the port plane to remain (actuate to) nominal; may operate the starboard plane to remain (actuate to) nominal; and may operate the dorsal rudder to remain at nominal.

The Segment Drive Subsystem 626 may be configured to augment any of the buoyancy actions of Blocks 930, 940, 950 with a complementary turn of the segment, in keeping with the turn target interpreted from the maneuver command. If, at Block 955, the turn target of the maneuver command is determined to request a turn to port, then at Block 960 onboard local control devices may operate the dorsal rudder to actuate to port. If instead, at Block 965, the turn target of the maneuver command is determined to request a turn to starboard, then at Block 970 onboard local control devices may operate the dorsal rudder to actuate to starboard. If instead, at Block 975, the turn target of the maneuver command is determined to request the current course be maintained, then at Block 980 onboard local control devices may operate the dorsal rudder to remain (actuate to) nominal.

A person of skill in the art will immediately recognize that 30 an advantageous implementation of the variable ballast shipping vessel control system 320 may employ any or all of a Navigation Subsystem 622, Train Glide Subsystem 624, and/or Segment Drive Subsystem 626 collocated upon a single host computing device or distributed among two or 35 more host computing devices. For example, and without limitation, the various components of the variable ballast shipping vessel control system 626 may be implemented in an application host/server onboard the lead segment 102. Also, for example, and without limitation, the various components of the variable ballast shipping vessel control system 626 may be implemented as redundant and concurrent 40 executables for system reliability.

Those skilled in the art will appreciate that the present disclosure contemplates the use of computer instructions 45 and/or systems configurations that may perform any or all of the operations involved in submersible vessel movement control. The disclosure of computer instructions that include Navigation Subsystem 622 instructions, Train Glide Subsystem 624 instructions, and/or Segment Drive Subsystem 626 instructions is not meant to be limiting in any way. Those skilled in the art will readily appreciate that stored 50 computer instructions and/or systems configurations may be configured in any way while still accomplishing the many goals, features and advantages according to the present disclosure.

Furthermore, those skilled in the art will appreciate that auxiliary components and/or adornments may be added to the designs of the various embodiments of the present invention as described above while still accomplishing the 55 many goals, features and advantages according to the present disclosure. For example, and without limitation, FIGS. 14, 15 and 16 illustrate additional means of reducing form drag during movement of the assembled vessel 100. Specifically, the spatial gap between the lead segment 102 and the immediately adjacent cargo segment 104 may be substantially filled by a lead slipstream cover 1002. Similarly, the respective spatial gaps between each cargo segment 104

and the immediately trailing cargo segment 104 (or, for the last cargo segment 104, the immediately trailing tail segment 106) may be substantially filled by a respective cargo slipstream cover 1004. As shown in FIG. 16, covering of inter-segment gaps with slipstream covers 1002, 1004 may give a variable ballast propulsion shipping vessel 100 of the present invention the “cigar” shape that is common to submarine design, but without compromising the advantageous degrees of freedom of movement between segments that facilitate variable buoyancy vessel propulsion as described hereinabove.

Referring to FIGS. 17 and 18, an exemplary embodiment of the variable ballast propulsion shipping vessel 100', herein referred to as “shipping vessel 100'”, is disclosed. It will be understood by those with ordinary skill in the art that the shipping vessel 100' can have similar applications in similar environments as described with reference to the shipping vessel 100 of FIG. 1. Examples of the applications include, but are not limited to, transporting removable cargo (e.g., fluid or dry bulk freight, goods in shipping containers) by travelling partially below or above a sea surface or under the sea (i.e., the submerged mode).

In some embodiments, the shipping vessel 100' includes a vessel segment 1008 defining a vessel body portion 1203. The vessel body portion 1203 includes a front portion 1213 and a rear portion 1214 longitudinally opposite to the front portion 1213 along an axis C-C of the shipping vessel 100'. In some embodiments, the front portion 1213 is defined along a direction of motion of the shipping vessel 100' and the rear portion is defined in a direction opposite to the direction of motion of the shipping vessel 100'. In some embodiments, the shipping vessel 100' also includes a vessel nose 1202 provided in the front portion 1213 of the vessel body portion 1203. In some embodiments, the vessel nose 1202 is defined at a bow of the vessel segment 1008. In some embodiments, the shipping vessel 100' also includes a vessel navigation light 1230 provided on the vessel nose 1202 for use as the safety beacon during night or during reduced visibility navigation of the shipping vessel 100. In some embodiments, the shipping vessel 100' also includes a plurality of impellers 1208 projecting at least partly outwardly from an exterior surface of the vessel segment 1008. As will be understood that the vessel nose 1202 of the present embodiment can be similar to the nose cone 202 and the plurality of impellers 1208 can be similar to the impeller 208 of FIG. 2. A movement of the vessel segment 1008 in the submerged mode is configured to be translated into a spinning of the impellers and the spinning of the impellers is converted, by at least one battery bank 312, 512 into an electrical energy and stored in the at least one battery bank 312, 512.

In some embodiments, the shipping vessel 100' defines a starboard side (as shown in FIG. 17) and a port side (as shown in FIG. 18). The starboard side of the shipping vessel 100' includes one or more hydrodynamic features provided on the vessel body portion 1203 of the vessel segment 1008 on both the starboard side and the port side. In some embodiments, the one or more hydrodynamic features includes, but not limited to, at least one pair of glide wings, for example 1220-A, 1220-B (correspondingly having a first pair of glide wings 1220-A1, 1220-A2 and a second pair of glide wings 1220-B1, 1220-B2), and at least one dorsal wing 1240. Each glide wing, for example, 1220-A1 or 1220-A2, of the at least one first pair of glide wings, for example, 1220-A includes at least one vane, for example, 1222-A1, 1222-A2 that is configured to be operable in combination with the at least one vane, for example, 1222-B1, 1222-B2.

and/or 1222-B2 of the corresponding other glide wings, for example, 1220-B1, 1220-A2, and/or 1220-B2. For example, the glide wing 1220-A1 of the first pair of glide wings 1220-A defines the vane 1222-A1 is operable independently or in combination with the vanes 1222-B1, 1222-A2, and/or 1222-B2 of the corresponding glide wings 1220-B1, 1220-A2, and/or 1220-B2 of the at least one pair of glide wings, for example, 1220-A or 1220-B. In some embodiments, the at least one vane, for example, 1222-A1 of the glide wing, for example, 1220-A1 is configured to be operated to change an angle of the at least one vane, for example, 1222-B1 with respect to the corresponding glide wing, for example, 1220-B. In an example, the at least one pair of glide wings, for example, 1220-A, and 1220-B is stowable through retraction or folding with respect to the vessel body portion 1203. In some embodiments, the shipping vessel 100 includes the at least one dorsal wing, for example, 1240 mounted on to the vessel body portion 1203. In some embodiments, the dorsal wing 1240 projects vertically in a direction perpendicular to the at least one pair of glide wings, for example, 1220-A, 1220-B. In some embodiments, the dorsal wing 1240 is positioned substantially equidistant from each of the glide wing, for example, 1220-A1 and 1220-A2 of the at least one pair of glide wings, for example, 1220-A. In some embodiments, the dorsal wing 1250 is positioned in between ballast systems, for example, 1304 and 1504 (discussed hereinafter) and/or a center of the vessel segment 1008. In some embodiments, the at least one dorsal wing 1240 includes a rudder 1242 which is configured to be operable independently or in combination with the at least one vane, for example, 1222-A1, 1222-B1, 1222-A2, 1222-B2, of one or more glide wings, for example, 1220-A1, 1220-B1, 1220-A2, 1220-B2 of the at least one pair of glide wings, for example, 1220-A, 1220-B. For example, the rudder 1242 of the at least one dorsal wing, for example, 1240 is configured to be operated to change an angle of the rudder 1242 with respect to the dorsal wing 1240. In some embodiments, the change of the angle of the at least one vane, for example, 1222-A1, 1222-B1, 1222-A2, 1222-B2 and/or the rudder 1242 also controls a pitch and a forward motion of the vessel segment 1008. In some embodiments, the shipping vessel 100' also includes an environmental profiling gear 1201 mounted on the vessel nose 1202 (or on the vessel body portion 1203). Examples of the environmental profiling gear 1201 include, but are not limited to, instruments for measuring temperature, salinity, and/or pressure. In some embodiments, the environmental profiling gear 1201 is mounted on the nose cone 1202 and/or to the vessel body portion 1203. In some embodiments, the shipping vessel 100' also includes one or more actuator motors (not shown) configured for actuating the rudder, for example, 1242 of the at least one dorsal wing, for example, 1240 and/or the at least one vane, for example, 1222-A1, 1222-B1, 1222-A2, 1222-B2. In some embodiments, the at least one battery bank, for example, 312, 512 is configured to deliver power to the actuator motors and/or the at least one control system 1320.

In some embodiments, the shipping vessel 100' also includes a lead section 2002 and a cargo section 2004. The cargo section 2004 is defined downstream of the lead section 2002 along the axis C-C. In some embodiments, the lead section 2002 includes the first pair of glide wings 1220-A with the respective vanes 1222-A1, 1222-A2. Further, the

cargo section 2004 includes the second pair of glide wings 1220-B with the respective vanes 1222-B1, 1222-B2. In some embodiments, the shipping vessel 100 also includes a tail section 106' defining a tail body portion 542. In some embodiments, the tail section 106' extends downstream of the cargo section 2004 along the axis C-C. In some embodiments, the tail section 106' is defined at an aft of the vessel segment 1008. In some embodiments, the tail section 106' is hingedly attached to the vessel segment 1008. In some embodiments, the tail section 106' is attached or coupled to the rear portion 1214 the vessel segment 1008 via one or more engaging means 1212 including, but not limited to, a ball-socket joint, a hinge joint, etc.

In some embodiments, the vessel body portion 1203 of the vessel segment 1008 includes a first access panel 1207 provided in the cargo section 2004 and a second access panel 1209 provided in the lead section 2002 of the shipping vessel 100'. The access panels 1207, 1209 are opened when the vessel segment 1008 is in the surfaced mode or when dry docked to allow maintenance access to components and systems that are deployed either partially or fully inside the vessel body portion 1203. In some embodiments, the shipping vessel 1008 includes the ballast systems, for example, a first ballast system 1304 and a second ballast system 1504 adjacently positioned to the first ballast system 1304. Referring to FIGS. 19 and 20, the first ballast system 1304 includes at least one first variable ballast tank, for example, 304A, 304B and the second ballast system 1504 includes at least one second variable ballast tank, for example, 504A, 504B. The first and second variable ballast tanks 304A, 304B, 504A, 504B are similar to the ballast tanks 304, 504, as discussed above with reference to the shipping vessel 100. The shipping vessel 100' includes one or more connecting means 1012 configured to connect the first ballast system 1304 with the second ballast system 1504. Examples of the connecting means 1012 include, but are not limited to, one or more electrical connecting means and/or mechanical connecting means similar to the electrical and mechanical connecting means, for example, connecting means 232, 432 and 212, 412, as shown in FIGS. 2 and 6, respectively. In some embodiments, the first ballast system 1304 is positioned in the lead section 2002 and the second ballast system 1504 is positioned in the cargo section 2004. In some embodiments, the at least one first variable ballast tank, for example, 304A, 304B is provided in the lead section 2002 and the at least one second variable ballast tank, for example, 504A, 504B is provided in the cargo section 2004.

In some embodiments, the vessel segment 1008 also includes at least one control system, for example, 1320. In some embodiments, the at least one control system 1320 is provided in the lead section 2002, the cargo section 2004, or both the lead section 2002 and the cargo section 2004. In some embodiments, the control system 1320 is configured to receive the subroute comprising the target peak, the target trough, the target course, and the target waypoint. In some embodiments, based on the received subroute, the control system 1320 is configured to selectively operate the at least one first variable ballast tank 304 and the at least one second variable ballast tank 504 to alter a travel state of the vessel segment 1008. The travel state of the vessel segment 1008 corresponds to and is configured to be altered between different buoyancies including, but not limited to, the positive buoyancy, the negative buoyancy, and the neutral buoyancy of the vessel segment 1008 based on the subroute. In some embodiments, each subroute comprises the start waypoint and the end waypoint. In some embodiments, an elemental glide maneuver is defined between the start way-

point and the end waypoint for the vessel segment 1008 from an initial peak depth down to trough depth, and back up to a subsequent peak depth. It is understood by those with ordinary skill in the art, that the control system 1320 of the shipping vessel 100' (of FIG. 18) can perform similar functions to those performed by the control system 320 (of FIG. 3) of the shipping vessel 100, as discussed above. As will be understood by viewing FIG. 12, the control system 1320 of the shipping vessel 100' can perform functions substantially similar to the control system 320 of the shipping vessel 100, as discussed above. For example, the at least one control system 1320 is configured to control the one or more hydrodynamic features (i.e., the at least one pair of glide wings 1220-A or 1220-B and/or the at least one dorsal wing 1240) to translate an underwater downward acceleration and an underwater upward acceleration into a desired direction as the pitch and/or the yaw of the shipping vessel 100. In some embodiments, in response to the functions performed by the control system 1320, the shipping vessel 100' executes the glide maneuver to glide up and down underwater along the glide path defined by the series of the target peaks and the target troughs to move the shipping vessel 100' underwater.

Referring to FIG. 19, an exemplary illustration of a cross-sectional view of the first ballast system 1304 of the shipping vessel 100' along an axis A-A (see FIGS. 17-18) is shown and described. In some embodiments, the first ballast system 1304 of the lead section 2002 includes the first battery bank 312' and a first battery charger 310' to charge the first battery bank 312. In the submerged mode of the shipping vessel 100', spinning of the impellers 1208 is converted by the first battery charger 310' into electrical energy for power storage into the first battery bank 312. In some embodiments, the first ballast system 1304 of the lead section 2002 includes a first compressed air tank 306', and a first air compressor 305' to air fill the first compressed air tank 306'. In some embodiments, the first compressed air tank 306' is configured to transfer air into the at least one first variable ballast tank 304 of the first ballast system 1304. In some embodiments, the first ballast system 1304 includes at least one first ballast intake and exhaust, for example, 30A2, 30B2. In some embodiments, the at least one control system 1320 (see FIGS. 17-18) includes a first control system 320' configured to control the at least one first ballast intake and exhaust, for example, 30A2 and/or 30B2 to selectively receive and expel a fluid including, but not limited to, water into and out of the at least one first variable ballast tank 304A, 304B. In some embodiments, the first control system 320' is configured to introduce the air into or expel the air from the at least one first variable ballast tank 304' to correspondingly expel the fluid from or introduce the fluid into the at least one first variable ballast tank 304A, 304B for purposes of changing buoyancy of the lead section 2002 of the vessel segment 1008.

Referring to FIG. 19, an exemplary illustration of a cross-sectional view of the second ballast system 1504 of the shipping vessel 100 along an axis B-B (see FIGS. 17-18) is shown and described. In some embodiments, the second ballast system 1304 of the lead section 2002 includes the second battery bank 512 and a second battery charger 510' to charge the second battery bank 512. In the submerged mode of the shipping vessel 100', the second battery bank 512 is configured to provide power to various electrical components of the shipping vessel 100', such as the plurality of actuator motors, the plurality of impellers 1208, etc. In some cases, at least one first battery charger 310' and the at least one second battery charger 510 is configured to provide

power to charge the at least one first battery bank 312' or the at least one second battery bank 512. In some embodiments, the second ballast system 1504 of the cargo section 2004 includes a second compressed air tank 506', and a second air compressor 505' to air fill the second compressed air tank 506'. In some embodiments, the second compressed air tank 506' is configured to transfer air into the at least one second variable ballast tank, for example 504A, 504B (of the second ballast system 1504). In some embodiments, the second ballast system 1504 includes at least one second ballast intake and exhaust, for example 50A2, 50B2, wherein the at least one control system 1320 (or the control system 320') is configured to control the at least one second ballast intake and exhaust, for example 50A2, 50B2, to selectively receive and expel water into and out of the at least one second variable ballast tank, for example 504A, 504B. In this regard, the at least one control system 1320 is configured the air to be introduced into or expelled from the at least one second variable ballast tank 504A, 504B to correspondingly expel or introduce water for purposes of changing buoyancy of the cargo section 2004 of the vessel segment 1008.

In some embodiments, the at least one control system 1320 is configured to selectively fill and expel a fluid from the at least one first variable ballast tank, for example, for example 304A, 304B and the at least one second variable ballast tank, for example 504A, 504B, to correspondingly change buoyancies in the at least one first variable ballast tank, for example 304A, 304B and the at least one second variable ballast tank for example 504A, 504B. Based on the change in buoyancies in the at least one first ballast tank, for example, 304A, 304B and the at least one second variable ballast tank, for example, 504A, 504B, the at least one control system 1320 is configured to alter the travel state of the vessel segment 1008. The at least one control system 1320 configures the compressed air tanks 306, 506' to transfer air into the at least one first variable ballast tank for example 304A, 304B, and the at least one second variable ballast tank for example 504A, 504B. The at least one control system 1320 is configured to air compressor 305, 505' to air fill the corresponding compressed air tank 306', 506. The at least one control system 1320 is configured the at least one ballast intake(s) and exhaust(s), for example 30A2, 30B2, 50A2, 50B2 to selectively receive and expel water into and out of the at least one first variable ballast tank, for example 304A, 304B and the at least one second variable ballast tank for example, 504A, 504B, respectively.

In some embodiments, the at least one control system 1320, similar to the control system 320, includes a computer processor and a non-transitory computer-readable storage medium having a plurality of instructions which, when executed by a computer processor. The computer processor of the at least one control system 1320 is configured to operate the vessel segment 1008 by transmitting one or more buoyancy commands (as shown in FIG. 12) to control the one or more hydrodynamic features of the vessel and modify the travel state. The buoyancy commands are transmitted by the computer processor (or by the at least one control system 1320) when the travel state of the vessel segment 1008 indicates the actual position that is not equal to the target waypoint of the vessel segment 1008. In some embodiments, the one or more buoyancy commands include a set neutral buoyancy command, a set negative buoyancy command, or a set positive buoyancy command.

In an example, the set neutral buoyancy command (block 860 of FIG. 12) is transmitted (by the at least one control system 1320) upon detection of an on-target condition between a target depth and an actual depth of the travel state

of the vessel segment 1008. Upon receiving the set neutral buoyancy command, the at least one control system 1320 is configured to retain the fluid within the at least one first and second variable ballast tanks, for example 304A, 304B, 504A, 504B at a current level of the fluid in the at least one first and second variable ballast tanks, for example, 304A, 304B, 504A, 504B. Thus, articulating the at least one vane, for example 1222-A1, 1222-A2, 1222-B1, 1222-B2 to the nominal position, and articulating the rudder 1242 to a laterally nominal position via at least one actuator motor (block 950 of FIG. 13). In some embodiments, the nominal position (or vertically nominal position) is defined when the vane 1222-A1, 1222-A2, 1222-B1, 1222-B2 having an angle close to 0 degree with respect to the corresponding glide wing 1220-A1, 1220-A2, 1220-B1, 1220-B2. In some embodiments, the laterally nominal position is defined when the rudder 1242 having an angle close to 0 degree with respect to the dorsal wing 1240.

In another example, the at least one control system 1320 is also configured to transmit the set negative buoyancy command (block 870 of FIG. 12) upon detection of a positive delta between the target trough and the actual depth of the travel state of the vessel segment 1008. Upon receiving the set negative buoyancy command, the at least one control system 1320 is configured to fluid/water filling of the at least one first and/or second variable ballast tanks, for example, 304A, 304B, 504A, 504B. Upon receiving the set negative buoyancy command, the at least one control system 1320 is also configured to articulate the at least one vane, for example 1222-A1, 1222-A2, 1222-B1, 1222-B2 to the down position, and/or articulate the rudder 1242 to the laterally nominal position via the at least one actuator motor (block 940 of FIG. 13). In some embodiments, the down position is defined when the vane 1222-A1, 1222-A2, 1222-B1, 1222-B2 having an angle greater than 0 degree with respect to the corresponding glide wing 1220-A1, 1220-A2, 1220-B1, 1220-B2.

Yet in another example, the at least one control system 1320 is also configured to transmit the set positive buoyancy command (block 880 of FIG. 12) upon detection of a negative delta between the target peak and the actual depth of the travel state of the vessel segment 1008. Upon receiving the set positive buoyancy command, the at least one control system 1320 is configured to air filling of the at least one first and/or second variable ballast tanks, for example, 304A, 304B, 504A, 504B. Upon receiving the set positive buoyancy command, the at least one control system 1320 is also configured to articulate the at least one vane, for example 1222-A1, 1222-A2, 1222-B1, 1222-B2 to the up position, and articulate the rudder 1242 to the laterally nominal position via at least one actuator motor (block 930 of FIG. 12). In some embodiments, the up position is defined when the vane 1222-A1, 1222-A2, 1222-B1, 1222-B2 having an angle greater than 0 degree with respect to the corresponding glide wing 1220-A1, 1220-A2, 1220-B1, 1220-B2, but in a direction opposite to the down position (as defined above).

In some embodiments, when the actual position of the travel state of the vessel segment 1008 is not equal to the target waypoint, the at least one control system 1320 is configured to operate the vessel segment 1008 by transmitting at least one travel command. Examples of the at least one travel command include, but are not limited to, a maintain heading command, a starboard turn command, and a port turn command. In an example, the at least one control system 1320 is configured to transmit the maintain heading command (block 894 of FIG. 12) upon detection of an

on-course condition between the target course and an actual heading of the travel state of the vessel segment **1008**. In another example, the at least one control system **1320** is configured to transmit the starboard turn command (block **892** of FIG. 12) upon detection of a port delta between the target course and the actual heading of the travel state the vessel segment **1008**. Yet in another example, the at least one control system **1320** is configured to transmit a port turn command (block **890** of FIG. 12) upon detection of a starboard delta between the target course and the actual heading of the travel state of the vessel segment **1008**.

Referring to FIG. 21, a method **2100** of operating the shipping vessel **100** is disclosed. It will be understood by those with ordinary skill in the art, the method of operating the shipping vessel **100**' and its application can be substantially similar to the method of operating the shipping vessel **100**. At step **2102**, the method includes receiving, by the at least one control system **1320**, the subroute comprising the target peak, the target trough, the target course, and the target waypoint of the vessel segment **1008**. Based on the received subroute, the method includes selectively operating, by the at least one control system **1320**, the at least one first variable ballast tank, for example **304A**, **304B** and the at least one second variable ballast tank, for example, **504A**, **504B** to alter the travel state of the vessel segment **1008** among the positive buoyancy, the negative buoyancy, and the neutral buoyancy. Further, at step **2104**, the method includes selectively filling and expelling of the fluid into and out of the at least one first variable ballast tank, for example **304A**, **304B** and the at least one second variable ballast tank, for example **504A**, **504B**, respectively, to correspondingly change buoyancies of the at least one first variable ballast tank, for example, **304A**, **304B** and the at least one second variable ballast tank, for example **504A**, **504B**. In addition, at step **2106**, the method includes altering, by the at least one control system **1320**, the travel state of the vessel segment **1008** based on the selective filling and expelling of the fluid.

In some embodiments, the method includes controlling, by the at least one control system **1320**, the one or more hydrodynamic features of the shipping vessel **100**' to translate an underwater downward acceleration and an underwater upward acceleration into a desired direction as at least one of pitch and yaw. In some embodiments, the shipping vessel **100**' executes the glide maneuver to glide up and down underwater along the glide path defined by the series of the target peak and the target trough to move the shipping vessel **100**' underwater.

In some embodiments, the method includes transmitting, by the at least one control system **1320**, the set neutral buoyancy command, the set negative buoyancy command, or the set positive buoyancy command for the shipping vessel **100**. For instance, the method includes transmitting the set neutral buoyancy command (block **860** of FIG. 12) upon detection of an on-target condition between the target depth and the actual depth of the travel state of the vessel segment **1008**. Upon receiving the set neutral buoyancy command, the method includes retaining the fluid within the at least one first and/or second variable ballast tanks **304**, **504**. Further, upon receiving the set neutral buoyancy command, the method also includes articulating the at least one vane, for example, **1222-A1**, **1222-A2**, **1222-B1**, **1222-B2** to the vertically nominal position, and articulating the rudder **1242** to the laterally nominal position via the at least one actuator motor (block **950** of FIG. 12). In addition, the method includes transmitting the set negative buoyancy command (block **870** of FIG. 12) upon detection of the positive delta between the target trough and the actual depth

of the travel state of the vessel segment **1008**. Further, upon receiving the set negative buoyancy command, the method includes performing water filling of the at least one first and second variable ballast tanks **304**, **504**. Furthermore, upon receiving the set negative buoyancy command, the method includes articulating the at least one vane, for example, **1222-A1**, **1222-A2**, **1222-B1**, **1222-B2** to the down position, and articulating the rudder **1242** to the laterally nominal position via the at least one actuator motor (block **940** of FIG. 12). In addition, the method includes transmitting the set positive buoyancy command (block **880** of FIG. 12) upon detection of the negative delta between the target peak and the actual depth of the travel state of the vessel segment **1008**. Further, upon receiving the set positive buoyancy command, the method includes performing air filling of the at least one first and second variable ballast tanks **304**, **504**. Furthermore, upon receiving the set positive buoyancy command, the method includes articulating the at least one vane, for example, **1222-A1**, **1222-A2**, **1222-B1**, **1222-B2** to the up position, and articulating the rudder **1242** to the laterally nominal position via at least one actuator motor (block **930** of FIG. 12).

In some embodiments, when the actual position of the travel state of the vessel segment **1008**' is not equal to the target waypoint, the method includes transmitting the at least one travel command. For example, the method includes transmitting, by the at least one control system **1320**, the at least one travel command including, but not limited to, the maintain heading command, the starboard turn command, or the port turn command. In an exemplary embodiment, the method includes transmitting the maintain heading command (block **894** of FIG. 12) upon detection of the on-course condition between the target course and the actual heading of the travel state of the vessel segment **1008**. In another, exemplary embodiment, the method includes transmitting the starboard turn command (block **892** of FIG. 12) upon detection of the port delta between the target course and the actual heading of the travel state of the vessel segment **1008**. In yet another exemplary embodiment, the method includes transmitting the port turn command (block **890**) upon detection of the starboard delta between the target course and the actual heading of the travel state of the vessel segment **1008**.

In some embodiments, the method includes defining, between the start waypoint and the end waypoint of the subroute, via the at least one control system **1320**, the elemental glide maneuver for the vessel segment **1008** and/or the shipping vessel **100**' from the initial peak depth down to the trough depth, and back up to the subsequent peak depth.

In some embodiments, the method or methods described above may be executed or carried out by a computing system including a tangible computer-readable storage medium, also described herein as a storage machine, that holds machine-readable instructions executable by a logic machine (i.e., a processor or programmable control device) to provide, implement, perform, and/or enact the above-described methods, processes and/or tasks. When such methods and processes are implemented, the state of the storage machine may be changed to hold different data. For example, the storage machine may include memory devices such as various hard disk drives, flash drives, CD, or DVD devices. The logic machine may execute machine-readable instructions via one or more physical information and/or logic processing devices. For example, the logic machine may be configured to execute instructions to perform tasks for a computer program. The logic machine may include one or more processors to execute the machine-readable instruc-

tions. The computing system may include a display subsystem to display a graphical user interface (GUI) or any visual element of the methods or processes described above. For example, the display subsystem, storage machine, and logic machine may be integrated such that the above method may be executed while visual elements of the disclosed system and/or method are displayed on a display screen for user consumption. The computing system may include an input subsystem that receives user input. The input subsystem may be configured to connect to and receive input from devices such as a mouse, keyboard or gaming controller. For example, a user input may indicate a request that certain task is to be executed by the computing system, such as requesting the computing system to display any of the above-described information or requesting that the user input updates or modifies existing stored information for processing. A communication subsystem may allow the methods described above to be executed or provided over a computer network. For example, the communication subsystem may be configured to enable the computing system to communicate with a plurality of personal computing devices. The communication subsystem may include wired and/or wireless communication devices to facilitate networked communication. The described methods or processes may be executed, provided, or implemented for a user or one or more computing devices via a computer-program product such as via an application programming interface (API).

Some of the illustrative aspects of the present invention may be advantageous in solving the problems herein described and other problems not discussed which are discoverable by a skilled artisan.

While the above description contains much specificity, these should not be construed as limitations on the scope of any embodiment, but as exemplifications of the presented embodiments thereof. Many other ramifications and variations are possible within the teachings of the various embodiments. While the invention has been described with reference to exemplary embodiments, it will be understood by those skilled in the art that various changes may be made and equivalents may be substituted for elements thereof without departing from the scope of the invention. In addition, many modifications may be made to adapt a particular situation or material to the teachings of the invention without departing from the essential scope thereof. Therefore, it is intended that the invention not be limited to the particular embodiment disclosed as the best or only mode contemplated for carrying out this invention, but that the invention will include all embodiments falling within the scope of the appended claims. Also, in the drawings and the description, there have been disclosed exemplary embodiments of the invention and, although specific terms may have been employed, they are unless otherwise stated used in a generic and descriptive sense only and not for purposes of limitation, the scope of the invention therefore not being so limited. Moreover, the use of the terms first, second, etc. do not denote any order or importance, but rather the terms first, second, etc. are used to distinguish one element from another. Furthermore, the use of the terms a, an, etc. do not denote a limitation of quantity, but rather denote the presence of at least one of the referenced item.

Thus, the scope of the invention should be determined by the appended claims and their legal equivalents, and not by the examples given.

That which is claimed is:

1. A shipping vessel, comprising:
 a vessel segment comprising:
 5 at least one first variable ballast tank; and
 at least one second variable ballast tank adjacently positioned to the at least one first variable ballast tank; and
 at least one control system configured to:
 10 receive a subroute comprising a target peak, a target trough, a target course, and a target waypoint; and
 selectively operate the at least one first variable ballast tank and the at least one second variable ballast tank to alter a travel state of the vessel segment among a positive buoyancy, a negative buoyancy, and a neutral buoyancy, based on the subroute; and
 15 the shipping vessel further comprising a lead section and a cargo section, wherein the lead section is defined upstream of the vessel segment and the cargo section is defined downstream of the lead section, and
 20 the at least one first ballast tank is provided in the lead section and the at least one second ballast tank is provided in the cargo section.

2. The shipping vessel of claim 1, wherein the at least one control system is provided in at least one of the lead section, the cargo section, or both the lead section and the cargo section, and wherein the at least one control system is configured to selectively fill and expel a fluid from the at least one first variable ballast tank and the at least one second variable ballast tank respectively to correspondingly change buoyancies in the at least one first variable ballast tank and the at least one second variable ballast tank and alter the travel state of the vessel segment.

3. The shipping vessel of claim 1, wherein the vessel segment comprises one or more hydrodynamic features, wherein the at least one control system is configured to control the one or more hydrodynamic features to translate an underwater downward acceleration and an underwater upward acceleration into a desired direction as at least one of pitch and yaw such that the shipping vessel executes a glide maneuver to glide up and down underwater along a glide path defined by a series of the target peaks and the target troughs to move the shipping vessel underwater.

4. The shipping vessel of claim 1, further comprising a tail section defining a tail body portion having a bow and extending downstream of the cargo section.

5. The shipping vessel of claim 4, wherein the tail section is hingedly attached to the vessel segment.

6. The shipping vessel of claim 3, wherein the one or more hydrodynamic features comprises:

55 at least one pair of glide wings projecting laterally outward from a vessel body portion of the vessel segment, wherein at least one glide wing of the at least one pair of glide wings defines at least one vane independently operable or in combination with the at least one vane of another glide wing of the at least one pair of glide wings, and the at least one pair of glide wings is stowable through retraction or folding; and

60 at least one dorsal wing mounted on to the vessel segment and projecting vertically in a direction perpendicular to the at least one pair of glide wings, wherein the at least one dorsal wing comprises a rudder.

7. The shipping vessel of claim 1, wherein the vessel segment comprises:

65 a compressed air tank configured to transfer air into the at least one first variable ballast tank and the at least one second variable ballast tank;

25

an air compressor configured to air fill the compressed air tank; and

at least one ballast intake and exhaust configured to selectively receive and expel water into and out of the at least one first variable ballast tank and the at least one second variable ballast tank respectively.

8. The shipping vessel of claim 6, further comprising: a plurality of actuator motors for actuating the corresponding rudder and at least one vane; and at least one battery bank configured to deliver power to the plurality of actuator motors, the at least one control system, or the plurality of actuator motors and the at least one control system.

9. The shipping vessel of claim 7, further comprising a plurality of impellers projecting at least partly outwardly from an exterior of the vessel segment, wherein a movement of the vessel segment in a submerged mode translates into a spinning of the impeller and the spinning of the impellers is converted, by the battery bank, into an electrical energy and stored in the at least one battery bank.

10. The shipping vessel of claim 6, wherein the at least one control system further comprises a computer processor and a non-transitory computer-readable storage medium having a plurality of instructions which, when executed by the computer processor, causes the computer processor to selectively operate the vessel segment by:

transmitting at least one of:

a set neutral buoyancy command upon detection of an on-target condition between a target depth and an actual depth of the travel state;

a set negative buoyancy command upon detection of a positive delta between the target trough and the actual depth of the travel state; or

a set positive buoyancy command upon detection of a negative delta between the target peak and the actual depth of the travel state,

while the travel state indicates an actual position that is not equal to the target waypoint of the vessel segment; and

40 performing at least one of:

upon receiving the set positive buoyancy command, air filling the at least one first and second variable ballast tanks, articulating the at least one vane to an up position, and articulating the rudder to a laterally nominal position via at least one actuator motor of the plurality of actuator motors;

upon receiving the set negative buoyancy command, water filling the at least one first and second variable ballast tanks, articulating the at least one vane to a down position, and articulating the rudder to the laterally nominal position via the at least one actuator motor; and

upon receiving the set neutral buoyancy command, retaining a fluid within the at least one first and second variable ballast tanks, articulating the at least one vane to a vertically nominal position, and articulating the rudder to the laterally nominal position via the at least one actuator motor.

11. The shipping vessel of claim 1, wherein when an actual position of the travel state of the vessel segment is not equal to the target waypoint, the at least one control system is configured to operate the vessel segment, by transmitting at least one of:

a maintain heading command upon detection of an on-course condition between the target course and an actual heading of the travel state;

26

a starboard turn command upon detection of a port delta between the target course and the actual heading of the travel state; or

a port turn command upon detection of a starboard delta between the target course and the actual heading of the travel state.

12. The shipping vessel of claim 1, wherein each subroute comprises a start waypoint and an end waypoint, further wherein between the start waypoint and the end waypoint, an elemental glide maneuver is defined for the vessel segment from an initial peak depth down to trough depth, and back up to a subsequent peak depth.

13. A method for operating a shipping vessel, wherein the shipping vessel comprising:

a vessel segment having at least one first variable ballast tank;

at least one second variable ballast tank adjacently positioned to the at least one first variable ballast tank; and at least one control system, the method comprising:

receiving, by the at least one control system, a subroute comprising a target peak, a target trough, a target course, and a target waypoint; and selectively operating, by the at least one control system, the at least one first variable ballast tank and the at least one second variable ballast tank to alter a travel state of the vessel segment among a positive buoyancy, a negative buoyancy, and a neutral buoyancy, based on the subroute;

transmitting, by the at least one control system, at least one of:

a set neutral buoyancy command upon detection of an on-target condition between a target depth and an actual depth of the travel state;

a set negative buoyancy command upon detection of a positive delta between the target trough and the actual depth of the travel state; or

a set positive buoyancy command upon detection of a negative delta between the target peak and the actual depth of the travel state.

14. The method of claim 13, further comprising:

selectively filling and expelling of a fluid into and out of the at least one first variable ballast tank and the at least one second variable ballast tank respectively, to correspondingly change buoyancies of the at least one first variable ballast tank and the at least one second variable ballast tank; and

altering, by the at least one control system, the travel state of the vessel segment based on the selective filling and expelling of the fluid.

15. The method of claim 13, further comprising:

controlling, by the at least one control system, one or more hydrodynamic features of the shipping vessel to translate an underwater downward acceleration and an underwater upward acceleration into a desired direction as at least one of pitch and yaw such that the shipping vessel executes a glide maneuver to glide up and down underwater along a glide path defined by a series of the target peak and the target trough to move the shipping vessel underwater.

16. The method of claim 13, wherein when an actual position of the travel state of the vessel segment is not equal to the target waypoint, the method comprises:

transmitting, by the at least one control system, at least one of:

27

- a maintain heading command upon detection of an on-course condition between the target course and an actual heading of the travel state;
  - a starboard turn command upon detection of a port delta between the target course and the actual heading of the travel state; or
  - a port turn command upon detection of a starboard delta between the target course and the actual heading of the travel state.
17. The method of claim 13, further comprising:
controlling one or more hydrodynamic features of the shipping vessel, wherein the one or more hydrodynamic features further comprising:
at least one pair of glide wings projecting laterally outward from a vessel body portion of the vessel segment, wherein at least one glide wing of the at least one pair of glide wings defines at least one vane independently operable or in combination with the at least one vane of another glide wing of the at least one pair of glide wings, and the at least one pair of glide wings is stowable through retraction or folding;
and
at least one dorsal wing mounted on to the vessel segment and projecting vertically in a direction perpendicular to the at least one pair of glide wings, wherein the at least one dorsal wing comprises a rudder,
- 10   15   20   25

28

- further wherein a plurality of actuator motors for respectively actuating the rudder and the at least one vane; and
performing at least one of:
upon receiving the set positive buoyancy command, air filling the at least one first and second variable ballast tanks, articulating the at least one vane to an up position, and articulating the rudder to a laterally nominal position via at least one actuator motor of the plurality of actuator motors;
upon receiving the set negative buoyancy command, water filling the at least one first and second variable ballast tanks, articulating the at least one vane to a down position, and articulating the rudder to the laterally nominal position via the at least one actuator motor; and
upon receiving the set neutral buoyancy command, retaining a fluid within the at least one first and second variable ballast tanks, articulating the at least one vane to a vertically nominal position, and articulating the rudder to the laterally nominal position via the at least one actuator motor.
18. The method of claim 13, further comprising:
defining, between a start waypoint and an end waypoint of the subroute, an elemental glide maneuver for the vessel segment from an initial peak depth down to a trough depth, and back up to a subsequent peak depth.
